(57) **CLAIM**

The ornamental design for a pan, as shown and described.

DESCRIPTION

FIG. 1 is a top perspective view of a pan showing my new design;

FIG. 2 is a left side view thereof;

FIG. 3 is a right side view thereof;

FIG. 4 is a front view thereof;

FIG. 5 is a back view of thereof;

FIG. 6 is a top view thereof; and,

FIG. 7 is a bottom view thereof.

The dash-dash broken lines in the drawings depict portions of the pan that form no part of the claimed design.

The long dash-short dash broken lines in the drawings define the bounds of the claimed design and form no part thereof.

1 Claim, 5 Drawing Sheets
